Inventor:

By Ezra A. Keller,
Att. Samuel N. Pond

UNITED STATES PATENT OFFICE.

EZRA A. KELLER, OF LA GRANGE, ILLINOIS.

UNLOADER.

Application filed July 1, 1922. Serial No. 572,236.

To all whom it may concern:

Be it known that I, EZRA A. KELLER, a citizen of the United States, residing at La Grange, in the county of Cook and State of Illinois, have invented certain new and useful Improvements in Unloaders, of which the following is a specification.

This invention relates to the general art of unloading appliances, and has reference 10 more particularly to power-operated apparatus designed to effect the unloading of sand, grain and other comparatively fine material in bulk from railway cars and its transfer to wagons, trucks or piles adjacent 15 to the railway track.

The apparatus of my present invention has been designed more especially to effect the rapid and economical unloading of sand from railway cars, and the main object of 20 the invention is to provide a comparatively simple, inexpensive and efficient unloading apparatus that can be suspended or otherwise supported adjacent to a railway track with capacity of bodily movement length- 25 wise of the latter and likewise swinging movement around its point of suspension or support between positions parallel with and crosswise of the track. Another object is to provide an apparatus of the character specified 30 including gathering and elevating mechanism operating directly on the material in the car and capable of being readily shifted by hand to reach the material at all points within the car, making it unnecessary 35 to shovel any appreciable amount of material from the corners and ends of the car into the reach of the gathering and elevating mechanism of the apparatus.

A further object of the invention is to provide 40 an apparatus of the character specified which shall be so mounted from or on its point of support that the parts thereof on opposite sides of said point of support shall substantially balance each other, thereby 45 rendering it easy to raise, lower and otherwise shift by hand the gathering and elevating mechanism. Other more specific objects and advantages of the invention will be apparent to persons skilled in the art as the 50 same becomes better understood by reference to the following detailed description, taken in connection with the accompanying drawings wherein I have illustrated a practical and approved embodiment of the invention

which in service has been found to operate satisfactorily, and in which— 55

Fig. 1 is a view partly in side elevation and partly in longitudinal and vertical section of the complete apparatus, portions of a railway car and of a wagon or truck alongside the latter being indicated in dotted lines to better illustrate the manner of using the apparatus; 60

Fig. 2 is a top plan view of the apparatus shown in Fig. 1; 65

Fig. 3 is an enlarged front elevation of the gathering mechanism and the lower end of the elevating conveyor;

Fig. 4 is an enlarged cross section through the delivery conveyor. 70

Fig. 5 is a view in side elevation of a differential pulley hoisting and lowering device for the unloader.

Referring to the drawings, at 10 is indicated in dotted lines a railway freight car of the type commonly employed for the transportation of coal, sand, and like material, and at 11 is indicated in dotted lines the body of a wagon or truck disposed alongside the car 10. 12 designates a trolley track, herein shown as an I-beam so mounted as to extend alongside of and parallel with the railroad track at an elevation somewhat above the top of the car 10. Mounted to travel on the track 12 is a trolley 13 carrying a block and pulley tackle taking the form of a well-known differential pulley hoist, shown in detail in Fig. 5, and comprising an upper pulley block or frame 14', rigidly connected differential grooved pulleys 14^a and 14^b journaled therein, a lower pulley block or frame 14, a grooved pulley 14^c journaled therein, and an endless chain 15 carried around said pulleys in such a manner that the lower pulley 14^c is supported on one side from the pulley 14^a and on its opposite side from the pulley 14^b. From the swivel hook 16 of the hoist is suspended by a bail 17 the entire apparatus of the unloader, including its motor and driving mechanism. 100 By pulling downwardly on the side of the chain 15 that hangs freely from the larger pulley 14^a the unloader is raised, and by pulling downwardly on the opposite side of the chain that hangs freely from the smaller pulley 14^b the unloader is lowered. More specifically, the lower ends of the bail 17 are pivoted to the outer sides of a pair 105

of parallel wooden beams or bars 18 that constitute the side frame members of the delivery conveyor. In and between the opposite ends of the beams 18 are journaled 5 outer and inner shafts 19 and 20, on which are mounted rollers 21 and 22, respectively, over and between which rollers is trained the endless carrier belt 23; the upper lap of the said belt being supported at frequent 10 intervals by a group of small rollers 24 as usual in this type of conveyor. To guide the edges of the upper and lower laps of the belt so as to maintain the latter always in true working relation to the rollers 21 and 15 22, small grooved guide sheaves 25 and 26 are mounted on the upper and lower edges of the beams 18 adjacent to the rollers 21 and 22, respectively.

To give a trough formation to the delivery conveyor I provide a pair of upwardly and outwardly inclined side wall strips 27 (Fig. 4) that overlie the longitudinal edge portions of the belt 23 and are conveniently supported by angle brackets 28 attached to 20 the beams 18. To the inner faces of the side wall strips 27 are attached flexible strips 29 of canvas, rubber, leather or any other suitable material, the lower edges of which overlap the upper lap of the main conveyor 25 belt 23, as clearly shown in Fig. 4.

The side beams 18 of the delivery conveyor frame extend a slight distance rearwardly of the inner belt roller 22, as indicated at 18', and to and between said beam 30 extensions 18' are secured by bolts 30 a pair of inclined parallel bars 31 extending above and below the plane of the delivery conveyor and constituting the side elements of a supporting frame for an elevating conveyor of the bucket type. To render the elevating conveyor frame rigid in its relation to the delivery conveyor frame, the side bars of the two frames are preferably connected by a pair of angle iron braces 32 and 33. Journaled in and between the upper 35 and lower ends of the conveyor frame bars 31 are a pair of shafts 34 and 35, respectively, fast on which are sprocket wheels 36 and 37, over which latter is trained an endless sprocket chain 38 carrying a series 40 of scoops or buckets 39. Secured to the frame bars 31 just above the level of the upper lap of the delivery conveyor 23 are a pair of forwardly extending guard plates 40 which overlap the receiving end of the delivery conveyor belt 23 throughout the dumping area of the buckets 39, preventing side-spill of the material as it drops from the buckets onto the delivery conveyor. Extending between the guard plates 40 is a transverse guard plate 41 located just above the receiving end of the delivery conveyor and tending to check and reduce back-spill 45 of the material.

As best shown in Fig. 3, the lower shaft

35 extends to some distance laterally of its bearings in the frame bars 31 and has attached thereto radial arms 42 carrying inclined or screw blades 43 which, sweeping through the material as the shaft 35 rotates, 70 operate to move the latter inwardly into the field of operation of the conveyor buckets as the latter round the lower end of the conveyor frame. I have herein shown a pair of these material-gathering blades 43 on 75 each side of the conveyor, the two blades being located 180° apart on the shaft, and the two blades on each side being set 90° from the two blades on the other side. This arrangement of gathering blades effects alternate feeds of the material to the buckets from the opposite sides, effectively supplementing the scooping action of the buckets and insuring the continuous filling of the latter so long as the gathering blades and 80 foot of the conveyor are maintained in the material. I have found that the spaced inclined blades disposed substantially as shown and described more effectively move the material into the path of the conveyor 85 buckets and into the buckets themselves than the plain screws which have heretofore been used for this purpose on the lower ends of elevating conveyors.

To provide for the angular and up and down shifting of the lower digging end of the gathering and elevating conveyor as well as of the delivery conveyor I provide a bail-shaped handle 44 that may be conveniently attached by collars or clips 45 to the sides of the conveyor frame extensions 100 18'; said handle extending sufficiently far in rear of the gathering and elevating conveyor to enable the same to be readily manipulated without danger of the feet of the operator getting into the range of the gathering blades or conveyor buckets. Also, to prevent the blades and buckets from striking the floor of the car, the lower end of the conveyor frame is equipped with a pair of 105 feet 46.

On the frame of the delivery conveyor and on the opposite side of the point of suspension from the elevating conveyor is mounted a platform 47, on which is mounted an electric motor 48. The armature shaft of the motor carries a pinion 49 meshing with a spur gear 50 on one end of a counter-shaft 51. On the opposite end of the counter-shaft 51 is a pinion 52 meshing with a spur gear 53 on the corresponding end of a second counter-shaft 54. On the other end of counter-shaft 54 is a sprocket wheel 55 driving a sprocket chain 56 that drivingly engages a sprocket wheel 57 on one end of the outer belt roller shaft 19. The last described mechanism constitutes the drive for the delivery conveyor belt; the counter-shafts 51 and 54 and their pinions and gears 115 constitute a suitable speed-reducing mech- 120 125 130

anism. The conveyor belt 23 constitutes a driving element for the rear belt-supporting roller 22 and its shaft 20. On one end of the shaft 20 is a sprocket wheel 57' which, 5 by a sprocket chain 58 drives a sprocket wheel 59 fast on the corresponding end of the upper shaft 34 of the elevating conveyor, by which the latter is driven. It will thus be seen that both conveyors and the 10 gathering mechanism are driven from a single motor itself mounted on and shiftable with the bodily and angular movements of the delivery conveyor. The belt 23 and roller 22 constitute a friction drive for the 15 elevating conveyor and the gathering mechanism, which is desirable on account of affording slip in the event of abnormal or breaking strains on the transmission mechanism due to the blades 43 encountering obstacles or overloads that prevent their normal functioning.

The operation of the unloader is probably clear from the foregoing description of its construction and organization, but may 20 be briefly outlined as follows. Assuming that a train of loaded cars brought to a position alongside of the trolley track 12 is to be unloaded, the apparatus is drawn along the track 12 to a position alongside 25 of a car at either end of the train, and the apparatus is then lowered sufficiently to bring the foot of the elevating conveyor and the gathering mechanism onto the top 30 of the load. The delivery conveyor is 35 swung laterally to a position where it overhangs the wagon or truck body 11, or a clear space of ground on which the material is to be piled. The motor having been started, the operator, by manipulation 40 of the handle 44, maintains the gathering mechanism and the foot of the elevating conveyor continuously in engagement with the material to be unloaded, by which the latter is rapidly gathered into the buckets, 45 elevated by the latter, dumped onto the delivery conveyor, and discharged from the outer end of the latter either into the wagon or truck 11 or onto the pile. As the unloading proceeds from one end of the car 50 to the other, the trolley 13 is shifted along the rail 12 as required to maintain the apparatus in its most advantageous working position. As soon as one car is unloaded, the apparatus is elevated sufficiently to 55 swing the elevating conveyor over the end of the empty car and the apparatus is then moved along the track 12 to a position opposite the next loaded car, and the described operations are repeated until the entire train 60 of cars is empty.

The apparatus being suspended at substantially mid-length from the swivel hook 16, and the bail 17 being pivotally connected to the delivery conveyor frame, it is possible to tilt the entire apparatus both hori-

zontally and vertically as may be required to secure the greatest working advantage; and this operation is greatly facilitated by supporting or suspending the apparatus at a point substantially coincident with its center of gravity. Also, the mounting of the motor on the apparatus itself greatly increases the flexibility of its movement and operations. While I have shown and described the apparatus as suspended from an 70 overhead trolley track, it is evident that it might be otherwise supported with capacity of bodily movement along the track, and without loss or reduction of its capacity of angular adjustment. Another advantage of 75 the described construction resides in the fact that, when not in use, the entire apparatus can be swung to a position beneath and in line with the trolley track 12 where it does not interfere with the movement of loaded 80 or empty trains on the railroad track.

While I have herein shown and described a practical embodiment of the invention which in practice has been found to operate satisfactorily, it is manifest that changes in 90 the details of structure and organization may be made without involving any departure from the operative principle of the invention or sacrificing any of the advantages thereof. Hence, I reserve all such 95 variations and modifications as fall within the spirit and purview of the appended claims.

I claim—

1. In an apparatus for unloading railway cars, the combination of a delivery conveyor, an elevating conveyor mounted on the receiving end of said delivery conveyor, a motor for driving said conveyors mounted on said delivery conveyor, and 100 means for supporting said delivery conveyor with capacity for angular swinging movement and bodily travel lengthwise of a railway car.

2. In an unloader of the character described, the combination with a delivery conveyor including parallel side bars, rollers journaled in and lying between said side bars, and a conveyor belt guided and supported by said rollers, said side bars extending rearwardly of the receiving end of said belt, of an elevating conveyor including parallel side bars lying across and bolted to the rearwardly extending portions of the side bars of said delivery conveyor, and braces connecting the upper end of said elevating conveyor to the side bars of said delivery conveyor.

3. In an apparatus for unloading railway cars, the combination of a delivery conveyor, an elevating conveyor mounted on the receiving end of said delivery conveyor, a motor for driving said conveyors mounted on said delivery conveyor, and means for pivotally suspending said delivery conveyor 125 130

at a point thereon between said elevating conveyor and said motor.

4. In an apparatus for unloading railway cars, the combination of a delivery conveyor, an elevating conveyor rigidly mounted on the receiving end of said delivery conveyor, a gathering mechanism on the lower end of said elevating conveyor, a motor for driving said conveyors and gathering mechanism mounted on said delivery conveyor, and means for pivotally suspending said delivery conveyor at a point thereon between said elevating conveyor and said motor and substantially coincident with the center of gravity of the assembly. 10

EZRA A. KELLER.
